Howard K. Brooks Inventor

By his Attorney

Clarence G. Campbell

UNITED STATES PATENT OFFICE.

HOWARD K. BROOKS, OF NEW YORK, N. Y.

GOLF-STROKE COUNTER.

Application filed April 7, 1922. Serial No. 550,401.

To all whom it may concern:

Be it known that I, HOWARD K. Brooks, a citizen of the United States, residing in the borough of Manhattan, in the county 5 of New York, city and State of New York, have invented certain new and useful Improvements in Golf-Stroke Counters, of which the following is a specification.

This invention relates to a golf stroke 10 counter, and more particularly to the adaptation and arrangement of the parts, as will be more fully hereinafter pointed out.

In playing golf one or more of the players 15 keeps the score card, on which is tallied the results of the playing for each hole, and this tally is entered by the score-keeper after all of the group playing together have finished each hole. This scoring does not, 20 however, provide for the scoring of each stroke which the individual player has made in making a particular hole, and therefore mistakes and disagreements arise at the time that the score-keeper is entering the 25 score for the particular hole finished.

My device is adapted to prevent such errors and misunderstandings, as each player in using my device is enabled to keep 30 an actual record of each stroke which he makes as soon as he has finished making the stroke, so that when he is through playing the hole my device will indicate accurately the number of strokes he has actually used in making that particular hole.

My device is also made so that it can be 35 suspended ready for use on the belt of the player so as to be always available, but not in the way; nor can it be lost as it is securely fastened to the belt. It also is 40 made in a very simple manner, so that there are no operating parts to get out of order, and it can be made at a very low cost because of its simplicity.

Referring to the drawings Figure 1 is a 45 vertical front view of my device suspended on a belt as used, but with the belt broken away at the ends for convenience in illustration; Figure 2 is a top plan view of the dial of my device; Figure 3 is a cross-section of Fig. 1 on the line 3-3; and Figure 4 is a top plan view of a dial adapted 50 to be secured to the wrist of the player.

In the drawings 4 is a dial having an inner circle 5, and between the inner circle 55 and the outside edge of the dial 4 are arranged at suitable intervals a series of

raised numerals 6. A hole 7 is cut out of the center of the dial 4 and raised members 8 are thrown up on the face of the dial 4 in radial alignment between the numerals 60 6 and the hole 7 opposite each of the numerals 6. The dial 4 has an extension member 9 which is integral with the dial, and in which there is cut out a slot 10. A hand 11 is mounted on the face of the dial 4 by 65 means of a rivet 12 which is riveted through the hole 7 and the hole 13 in one end of the hand 11, so that the hand 11 can swing freely around said rivet 12. The hand 11 also has a depressed member 14 on its under side in a position adapted to register 70 with the raised members 8 on the face of the dial 4 as the hand 11 is turned. The hand 11 also has an upturned spring portion 15 which serves as a finger member for 75 the user of my device. The upwardly bowed portion 15 also functions as a tension means whereby the free end of the hand 11 is maintained in frictional contact with the face of the dial 4 and more particularly in interlocked position when brought into registration 80 with the various indications thereon.

A strap 16 is adapted to pass through the slot 10, thereby suspending the dial 4, and said strap 16 has a buckle 17 of usual construction so that the strap 16 being passed 85 around a belt 18, which is worn around the waist of the player, can be fastened thereto in the usual well-known manner.

In using my device the player will fasten 90 the device around the belt 18 as indicated in Fig. 1, and the numerals 6 on the face of the dial 4 will be arranged, as indicated in Fig. 1, so that they can be easily and quickly read by the player as he looks down 95 at the same while it is hanging on his belt. When the first stroke is completed by the player he will then take hold of the hand 11 by means of the finger member 15 and turn the hand, which rested on numeral 0, 100 to 1, whereby the depressed member 14 will register on the raised member 8 in regular alignment with the numeral 1. After the second stroke has been made by the player he will then move the hand 11 in the same 105 way from the numeral 1 to the numeral 2, and the raised member 8 which is registered in the depressed member 14 merely retains the hand 11 sufficiently to prevent accidental movement, but not sufficiently to interfere 110 with the intended movement by the player from one numeral to another. This proc-

ess continues until the player has made the hole to which he is playing when the number of strokes used in attaining that hole will be indicated on the dial, and will be given by the player to the score-keeper, and the player will then return the hand 11 to the numeral 0 and proceed as before described.

It will be understood that the numerals 6 may be raised as illustrated and described herein, or may be stamped or printed or placed on the dial 4 in any suitable manner, and the device shown is not intended as a limitation, as other variations may be made without departing from the spirit of the invention. The dial 4 may, if preferred, have a second extension member 9 on the opposite side of the dial 4, said second extension member 9 also being provided with a slot 10 whereby the strap 16 will pass

through both of said slots 10 so that the dial 4 may be fastened by means of the strap 10 to the wrist of the player.

I claim:

In a golf stroke counter the combination of a dial having a series of numbers arranged on the face and near the edge thereof, and a hand pivotally mounted on the dial adapted to be moved into registration with any of the numbers on the face of the dial, said hand intermediate of its length having an upwardly bowed portion to facilitate the turning of said hand over the dial, said bowed portion constituting in effect a spring to maintain the free end of the hand in contact with the face of the dial.

In testimony whereof I affix my signature.

HOWARD K. BROOKS.
